(Cl. D56—4)

To all whom it may concern:

Be it known that I, Devendra Nath Sharma, a subject of the King of Great Britain, residing in London, Essex County, England, have invented a new, original, and ornamental Design for a Combined Portable Radio Receiver, Camera, Clock, and Cigarette Lighter, of which the following is a specification, reference being had to the accompanying drawing, forming part thereof.

Fig. 1 is a side elevational view of a combined portable radio receiver, camera, clock and cigarette lighter;

Fig. 2 is a top plan view;

Fig. 3 is an end elevational view; and

Fig. 4 is an elevational view opposite that shown in Fig. 3.

I claim:

The ornamental design for a combined portable radio receiver, camera, clock, and cigarette lighter, as shown.

DEVENDRA NATH SHARMA.
